UNITED STATES PATENT OFFICE.

WILLIAM H. SHOFTER, OF BARBERTON, OHIO, ASSIGNOR TO THE DIAMOND MATCH COMPANY, OF CHICAGO, ILLINOIS, A CORPORATION OF ILLINOIS.

COMPOSITION-APPLYING DEVICE FOR BOOK-MATCH MACHINES.

Application filed February 4, 1922. Serial No. 534,258.

To all whom it may concern:

Be it known that I, WILLIAM H. SHOFTER, a citizen of the United States, and resident of Barberton, in the county of Summit and 5 State of Ohio, have invented certain new and useful Improvements in Composition-Applying Devices for Book-Match Machines, of which the following is a specification.

10 This invention relates to means for applying match-ignition material to match-book covers and the like; having reference, more especially, to an improvement in composition applying devices of the general character described in Letters Patent of the 15 United States No. 1,042,472, dated October 29, 1912.

The machine set out in said patent includes a carrier whereby spaced-apart match books are advanced in close relation to the periphery of a rotating wheel by means of which ignition "paint" is transferred from a tank to the fastened cover folds of the match books. In the practical operation of 25 the machine a doctor or gauge plate associated with the wheel regulates the quantity of material carried up from the contents of the tank by the wheel and applied to the covers. The composition at the edges of 30 the tank becomes hard, and fragments of the hard material sometimes break off and lodge between the gauge plate and the wheel; thereby preventing the proper transference of the composition to the match books. This results in the production of a 35 number of imperfect books before the attendant observes the defect. Sometimes a similar trouble is caused by a broken splint which enters the composition and works 40 around in the tank until the splint becomes lodged between the wheel and the gauge plate.

The object of my invention is to overcome the difficulties above mentioned, and to 45 that end I provide the composition applying wheel with peripheral projections which cooperate with the gauge plate to prevent the lodgment of foreign matter between the wheel and the plate, as will be hereinafter 50 described and claimed.

In the drawings—

Figure 1 is a side elevation, partly in section, of composition applying mechanism

embodying my invention, showing a portion of a match-book carrier, and adjuncts.

Fig. 2 is a plan of the said mechanism showing parts of the carrier.

Fig. 3 is a side elevation of the composition applying wheel, showing the gauge-plate and its support in section, and also indicating the path of travel of the match-books above the wheel.

Fig. 4 is a plan of the wheel and gauge plate.

Fig. 5 is a perspective view of the gauge plate detached.

Referring to the drawings, 10 designates a part of an endless flexible carrier for match-books, said carrier, in the form illustrated, comprising hingedly connected link members in which match cards (as *a*) and covers (as *b*) (with the end folds of the covers projecting beyond the carrier) are assembled and bound together in book form; thence transported to and past a structure 75 whereby frictional ignition substance of the consistency of paint is applied exteriorly to the under surfaces of the projecting end folds of the covers, and thence carried through an extended drying path.

The paint-applying structure, in the particular form shown, comprises a standard 11 provided with posts 12, 13 having suitable bracket arms 14 supporting a track section 15 for the carrier. On the standard is also supported, beneath the carrier, a tank 16 adapted to contain the ignition composition. Mounted to rotate within the tank is a wheel 17 the periphery of which is adapted to carry up the composition into the path of the projecting folds of the covers, and thus apply the composition to the latter during their travel. This wheel is fast on a shaft 18 having its bearing in the post 13 on the standard and being provided with a spur wheel 19 in mesh with a pinion 20 on a shaft 21 which has its bearing in a bracket 22 on the standard. The pinion meshes with a suitably-disposed spur wheel 23 fast on a shaft 24 which has its bearings in the post 12 and is provided with a gear wheel 25 in mesh with rack teeth 26 on the links of the carrier.

On one end of the shaft 21 is a sprocket wheel 27 which is connected with and driven from a suitable source of power; and hence

the gears 19, 23 and their respective shafts are concurrently rotated in such a manner that the gear 25 advances the carrier 10 and the shaft 18 rotates the composition applying wheel.

Embracing the rim of the wheel is the forked end of an angular gauge plate 28, the active portion of which comprises an edge 29 which is appropriately spaced from the periphery of the wheel to determine the thickness of the film of composition carried up to the book covers by the wheel. The plate is adjustably affixed to the adjacent bracket arm 14, preferably by means of a set-screw 30 passing through a slot 31 in the plate.

According to my invention the periphery of the wheel is provided with a series of equally-spaced projections 32 which extend beyond the periphery a distance equal to the depth of composition to be carried up and deposited on the covers. This is usually about $\frac{1}{16}$ of an inch. In the present instance four projections are provided, the same being constituted by hard metal inserts in the periphery of the wheel. The rotation of the wheel is so timed in relation to the travel of the carrier that the book covers are acted upon by the peripheral surface of the wheel between the projections, such projections in their travel clearing the books.

By the construction above described it will be seen that if any foreign matter, such, for example, as fragments of hard composition or loose splints, enter between the wheel and the gauge plate, the peripheral projections will co-act with the gauge plate to break up such matter or will carry the matter past the plate, thus insuring a uniform application of the composition to the book-covers.

It is to be understood that my invention is not limited to the specific construction herein disclosed, as the same may be modified within the principle of my invention and the scope of the appended claims.

I claim—

1. The combination with a carrier for a

succession of separated articles, of a container for ignition material, a wheel mounted to rotate in said container and to transfer the material therefrom to the surface of said articles, said wheel having spaced-apart peripheral projections, a gauge plate adjacent the periphery of the wheel and the path of rotation of said projections, and means for rotating said wheel in synchronism with the travel of the articles whereby the peripheral portions of the wheel between the projections apply the material to the articles and the projections escape the articles.

2. The combination with a carrier for a succession of separated match-books, of a container for ignition material, a wheel mounted to rotate in said container and to transfer the material therefrom to the said books, said wheel having in its periphery a series of regularly spaced projecting inserts, a gauge plate adjacent the periphery of the wheel and the path of the projecting ends of the inserts, and means for rotating said wheel in synchronism with the travel of the books whereby the peripheral portions of the wheel between the inserts apply the material to the match-books and whereby the projecting ends of the inserts escape the books.

3. In means for applying match ignition composition to book-matches, a tank, a composition applying wheel therein having peripheral projections, and a plate having a forked end embracing the periphery of the wheel, said end having an edge portion spaced from the wheel to constitute a gauge to determine the thickness of the material which is carried up by the periphery of the wheel, said edge portion co-operating with the said projections to break up fragments of hard substances.

Signed at Barberton, in the county of Summit and State of Ohio, this 1st day of February A. D. 1922.

WILLIAM H. SHOFFTER.
